[57] **CLAIM**

The ornamental design for a single use fluid dispensing container, as shown and described.

DESCRIPTION

FIG. 1 is a perspective view of a single use fluid dispensing container showing my new design;

FIG. 2 is a top plan view thereof;

FIG. 3 is a front elevational view thereof; the rear elevational view being a mirror image thereof;

FIG. 4 is a left side elevational view thereof; the right side elevational view being a mirror image thereof;

FIG. 5 is a bottom plan view thereof;

FIG. 6 is a perspective view of a second embodiment of FIG. 1;

FIG. 7 is a top plan view of FIG. 6;

FIG. 8 is front elevational view of FIG. 6; the rear elevational view being a mirror image thereof;

FIG. 9 is a left side elevational view of FIG. 6; the right side elevational view being a mirror image thereof; and,

FIG. 10 is a bottom plan view of FIG. 6.

FIG. 1
